LADY'S UNDERGARMENT

Theodore J. Smutny, New York, N. Y., assignor
to Collegiate Manufacturing Co., Inc., New
York, N. Y., a corporation of New York

Application December 1, 1937, Serial No. 177,396

5 Claims. (Cl. 2—73)

The invention relates to wearing apparel, especially to undergarments such as ladies' slips. Its advantages, however, are also apparent when embodied in the fabrication of any intimate garment of this type, for instance, a chemise.

More particularly, the invention relates to an undergarment or slip of the general type illustrated in my Patent No. 2,053,227, dated September 1, 1936, which garment embodies certain improvements in the fabrication thereof, including the assembly of certain of the component portions thereof in which the material is assembled with the duplex panels constituted of bias cut material.

15 The present application is a continuation, in part, of my application, Serial Number 157,469, filed August 5, 1937, maturing into Patent No. 2,101,604 dated December 7, 1937.

An object of the present invention is to provide a garment of this general class, and particularly an improved construction of the type claimed in my said copending application, which will overcome certain difficulties and disadvantages characterizing an undergarment in which separate panels or pieces of material are joined, for instance, by stitching, so as to constitute a weak point of juncture where the material has a tendency to give and to tear by reason of the absence of elasticity in the material at the point of such juncture.

It is well recognized by those skilled in the art of fabricating slips, chemises or the like, that the weakest point of the garment is at the portion thereof constituting a V-type juncture of the two yokes of material in both the front and the back sections of the garment. When the wearer of such a garment indulges in any activity, bringing into play a movement of the shoulders, the strains and stresses produced by such movement are transmitted to the rather closely fitted garment, the tendency of the material of the garment is to give at the point of such juncture of the two yokes. As the point of juncture is very firm and therefore is characterized by very little, if any, elasticity, the material immediately adjacent the point of juncture is placed under an undue strain and eventually tears or otherwise disintegrates so that any advantages gained through the cutting of the material, constituting the component parts of the garment, on the bias is nullified.

50 The primary object of fabricating a slip or similar garment and assembling panels of material cut on the bias is to give elasticity and a degree of resiliency to the undergarment, so that ordinary movements of the wearer can be taken up and

compensated for by the bias. Such elasticity and resiliency, however, are lateral or sidewise elasticity and resiliency, and movements of the wearer of the garment involving other than the ordinary muscular action as in walking or in assuming a sitting position, are not compensated by the bias cutting of the material of the garment.

5 In accordance with the present invention, I provide an undergarment of this general class, including a slip and a chemise, so as to impart to such garments a freedom from strains and stresses that might otherwise be imparted by a free swinging motion, both sidewise and longitudinally. I accomplish this object by providing in the back of the garment, a cut-out substantially at the center and above the waistline, and inserting into such cut-out a strip of elastic which is thus positioned at the point of the garment where in the usual construction of such slip the two solid yoke pieces are joined. Such insert so disposed will have a circumferential component of elasticity as well as a component of elasticity at a right angle thereto, or in other words, the insert is so positioned as to have its principal direction of stretch at an angle to each of the edges of the cut-out. By this construction, a free movement of the wearer is permitted without binding and providing the utmost comfort during periods of activity of the wearer not only during indulgence in active working or recreational movements, but in the course of any movement in which a strain or stress would otherwise be imparted to the point of juncture of the two solid yoke pieces. Thus, for example, if a wearer in moving about raises one shoulder, the strain is absorbed by the elastic stretching a small degree longitudinally or in the direction of its free edge. No discomfort will thus be experienced by the wearer because of any binding action of the slip. If the wearer has to stoop over, the slip will expand with the expansion of the various parts of the body, permitted by the slight stretching of the elastic strip, so that the slip will stay in perfect position on the body without undue strain placed thereon.

45 I am aware that with certain types of undergarments, for instance, that embodying a brassière with a body encircling portion so that the whole constitutes a slip, a strip of elastic is inserted laterally across the back; in such garment, however, the elastic strip has only a sidewise or lateral parallel expansion. With the angular movement possible with my novel slip in which the elastic is capable of stretching along a line at an angle to the horizontal, a greater free- 50

dom of movement, without binding and with no discomfort, is possible. Furthermore, with such brassière type of slip the elastic strip is necessarily of some length and can therefore be applied only to a "low-cut" (i. e. low back) slip.

In my said copending application, Serial No. 157,469, I describe and claim an elastic insert constituted of two separate pieces so positioned as to partially overlap. In accordance with the present invention, I overcome the manufacturing difficulties encountered in cutting two separate elastic sections of generally triangular configuration, by providing a single strip of elastic material in the form of a parallelogram, in which the ribs extend longitudinally of the strip, which strip may be folded along the short diagonal thereof so as to constitute a single piece of elastic material having a continuous, closed, bottom edge and two portions, one partially overlapping the other, for disposition within the cut-out in the back of the garment in substantially the same position as the two separate pieces in the structure of my copending application.

In accordance with such improved embodiment of my invention, I secure substantially the same results with the great advantage in the commercial production of the garment to which the invention is applied, of being enabled to cut the elastic material in pieces which can then be folded so as to have a continuous, closed lower edge and form the two partially overlapping sections.

The folded elastic strip characterizing my novel slip may be inserted into a garment of the type disclosed in my Patent No. 2,053,227 hereinabove referred to, without distorting or nullifying the feature of such slip, i. e. its reversibility, but it is to be understood that my novel construction, as hereinafter more particularly described, is equally applicable to any other type of slip, chemise, or intimate garment of the same general character.

In the drawing, in which I have illustrated my invention as embodied in a slip, Fig. 1 is a view in rear prospective of the garment; Fig. 2 is an enlarged detail view of the upper central portion of the rear section of the slip, showing the elastic insert; Fig. 3 is a section on the line 3—3 of Fig. 2; Fig. 4 is a section on the line 4—4 of Fig. 2; Fig. 5 is a plan view of the strip of elastic material before it is folded; and Fig. 6 is a plan view of the folded strip showing the manner of forming the two elastic portions of the insert.

Referring more particularly to the drawing, the slip comprises a body-encircling tubular portion 10, to the upper edges of which is secured by lines of stitching 11, the bust-encircling portion 12, constituted of a plurality of duplex panels 13, 14, 15 and 16, of which the first two are the rear panels and the latter two the front panels.

In accordance with my invention, the two rear panels 13 and 14, instead of being connected by a V-joint to each other and to the body portion of the slip, have their apices cut off to form a substantially rectangular cut-out, into which cut-out is placed and secured a piece of elastic material folded so as to constitute sections 17 and 18, partially overlapping, and secured along their vertical edges to the panels 13 and 14 by stitching 19 and 20, and to the body of the garment by stitching 21 and 22.

The elastic insert, as shown in Fig. 5, comprises a strip of ribbed elastic material of substantially parallelogram configuration, the ribs running longitudinally of the strip. In the construction of my novel garment, such elastic strip is folded

along its short diagonal so as to produce triangular sections 17 and 18 in which the ribbing in one is disposed perpendicularly to the ribbing in the other. In applying the folded elastic insert to the garment, the two opposite parallel and perpendicular sides thereof are secured to the opposite panels of the bust encircling portion of the garment, being secured within the duplex panels by stitching, with the hypotenuse or longest edges 23 and 24 of the triangular portions 10 crossing each other in substantially the upper center of the rear section of the slip.

As shown in Fig. 3, the tubular body portion 10 is first secured by stitching 21 to the continuous, closed bottom edge of the insert designated broadly as 26 and then turned downwardly at the upper center thereof to constitute the inturned edge 25. The insert 26 is then secured to the body portion by stitching 22, passing through the double thickness of elastic and the body portion.

The elastic inserts 17 and 18 are preferably of ribbed construction, with the ribs thereof disposed as shown in Fig. 2. The inserts are thus interposed in the space between the adjacent edges of the panels 13 and 14, on the bias, so as to have 25 their principal direction of stretch at an angle to each of the edges of the cut-out, whereby, when a pull is exerted, during movements of the wearer, as by bending or otherwise moving the shoulders, or either of them, the elastic insert is 30 capable of stretching in the direction of the parallel ribs. As a matter of fact, such pull upon the apex of the substantially triangular insert effects a flexing of the longest edge 23 or 24 whereby such edge assumes a somewhat curved, ex 35 tended delineation, and thus prevents pull on the opposite panel of the garment section, whereby binding or an otherwise uncomfortable stress would be produced.

To prevent bulging of the elastic insert portions 17 and 18 when undergoing stretching, I prefer to stitch a portion of the diagonal edge of one to the underlying portion, as at 27.

While I have described a particular embodiment of my invention, and have illustrated its application to a particular type of intimate garment, it is obvious that it may be applied in the fabrication of any design or type of such garment, and that various changes therein, particularly in the disposition and configuration of the elastic inserts, so long as their advantages and general features, hereinabove set forth, are embodied or retained, may be made without departing from my invention.

I claim:

1. An intimate garment of the class described, comprising a tubular body member of material cut on the bias and adapted to encircle the body of the wearer below the bust line, and an upper member of material cut on the bias and adapted 60 to encircle the body in the bust region, said upper member having panels at the back of the garment, the upper edge of the back of the garment having a substantially U-shaped cut-out, the lower edge of the cut-out being continuously horizontal, an elastic insert, having a continuous horizontally disposed bottom edge secured to the lower edge of the cut-out, the side edge of the insert being secured to a side edge of the cut-out, said insert being positioned with its principal direction of stretch at an acute angle to the lower and side edges of the cut-out, whereby upon bodily movement of the wearer strain is reduced at the point of juncture of the edges of the cut-out and a freely swinging movement of the body is per 70 75 80 85 90 95 100

mitted without binding or other discomfort to the wearer.

2. An intimate garment of the class described, comprising a tubular body member adapted to encircle the body of the wearer below the bust line, and an upper member adapted to encircle the body in the bust region, the upper edge of the back having a cut-out substantially at the center, said cut-out having bottom and side edges, 10 said body member and upper member being joined at the back of the garment by an elastic insert secured at its edges to the edges of the cut-out and so positioned as to have its principal direction of stretch at an acute angle to each of the edges of the cut-out, said elastic insert being constituted of a strip of elastic material of a configuration in the form of a parallelogram, folded along its short diagonal to form two partially overlapping sections, a portion of the diagonal edge of one of 15 said insert sections being stitched to the underlying material of the other insert section, whereby upon bodily movement of the wearer, strain is reduced at the point of juncture of the edges of the cut-out and a freely swinging movement of the body is permitted without binding or other discomfort to the wearer.

20 3. An intimate garment of the class described, comprising a tubular body member adapted to encircle the body of the wearer below the bust line, and an upper member adapted to encircle the body in the bust region, the upper edge of the back having a cut-out substantially at the center, 25 said cut-out having bottom and side edges, said body member and upper member being joined at the back of the garment by an elastic insert secured at its edges to the edges of the cut-out and so positioned as to have its principal direction of stretch at an acute angle to each of the edges of the cut-out, said elastic insert being constituted of a strip of ribbed elastic material of a configuration in the form of a parallelogram, folded along its short diagonal to form two partially overlapping sections, the ribbing of one section being substantially perpendicular to the ribbing of the other, whereby upon bodily movement of the wearer, strain is reduced at the point of juncture of the edges of the cut-out and a freely swinging movement of the body is permitted without binding or other discomfort to the wearer.

4. An intimate garment of the class described, comprising a tubular body member adapted to encircle the body of the wearer below the bust line, and an upper member adapted to encircle the body in the bust region, the upper edge of the back having a cut-out substantially at the center, said

cut-out having bottom and side edges, said body member and upper member being joined at the back of the garment by an elastic insert secured at its edges to the edges of the cut-out and so positioned as to have its principal direction of stretch at an acute angle to each of the edges of the cut-out, said elastic insert being constituted of a strip of elastic material of a configuration in the form of a parallelogram, folded along its short diagonal to form two partially overlapping sections, a portion of the diagonal edge of one of 10 said insert sections being stitched to the underlying material of the other insert section, whereby upon bodily movement of the wearer, strain is reduced at the point of juncture of the edges of the cut-out and a freely swinging movement of the body is permitted without binding or other discomfort to the wearer.

20 5. An intimate garment of the class described, comprising a tubular body member of material cut on the bias and adapted to encircle the body of the wearer below the bust line, and an upper member of material cut on the bias and adapted to encircle the body in the bust region, said upper member having panels at the back of the garment, the upper edge of the back having a cut-out substantially at the center, said cut-out having bottom and side edges, the latter being at an angle to the bottom edge, an elastic insert secured at its edges to the edges of the cut-out, the insert also having continuous horizontally disposed bottom edges secured to the lower edges of the cut-out, one side edge of the insert being secured to the lower edges of the cut-out, one side edge of the insert being secured to a side edge of the cut-out, 30 35 said insert being positioned so that its principal direction of stretch is at an acute angle to each of the edges of the cut-out, said elastic insert being constituted of a strip of elastic material of a configuration in the form of a parallelogram, folded along its short diagonal to form two partially overlapping sections, the upper edges of the two sections constituting the elastic insert, being substantially in alignment with the upper edges of the garment panels to which they are secured, 40 45 whereby upon bodily movement of the wearer, strain is reduced at the point of juncture of the edges of the cut-out and a freely swinging movement of the body is permitted without binding or other discomfort to the wearer.

50 THEODORE J. SMUTNY.
